[57] CLAIM

The ornamental design for a television receiver, as shown and described.

DESCRIPTION

FIG. 1 is a front, top and right side perspective view of a television receiver showing our new design;

FIG. 2 is a rear, bottom and left side perspective view thereof;

FIG. 3 is a front elevational view thereof with the extendable television aerial retracted and aligned parallel with the top of the television receiver housing;

FIG. 4 is a top plan view thereof;

FIG. 5 is a rear elevational view thereof;

FIG. 6 is a bottom plan view thereof;

FIG. 7 is a right side elevational view thereof;

FIG. 8 is a left side elevational view thereof; and

FIG. 9 is a view like FIG. 1 with the slidable cover in projected position.

*Fig. 1**Fig. 2**Fig. 3**Fig. 4**Fig. 5**Fig. 6**Fig. 7**Fig. 8**Fig. 9*
